UNITED STATES PATENT OFFICE.

JAMES ALBERTSON AND DANIEL W. MARMON, OF RICHMOND, INDIANA.

IMPROVEMENT IN BELT-TIGHTENERS.

Specification forming part of Letters Patent No. 122,345, dated January 2, 1872.

Specification describing a certain Improvement in Belt-Tighteners, invented by JAMES ALBERTSON and DANIEL W. MARMON, of Richmond, in the county of Wayne and State of Indiana.

In grinding-mills which have their driving-pulleys upon vertical spindles, and in various other kinds of machinery where the pulleys which give motion thereto are similarly arranged, it becomes necessary to provide a suitable receptacle for the belt to rest upon when it has been loosened from its contact with the pulleys around which it passes, and to so arrange this receptacle that the belt shall be held in such a position that upon the application of the belt-tightener the machinery may be at once put in motion; and it is indispensable for the preservation of the belt that when it is in use its lower edge should be kept clear from contact with the shelf upon which it rests while idle. To secure the result just named is the object of our present invention, which consists in the construction, combination, and arrangement of the parts of which it is composed, substantially in the manner shown, as a consequence of which a belt which has been loosened from two vertical pulleys and allowed to drop upon a shelf or table may be pressed upon by a roller and thus brought in contact with such pulleys, and, so soon as it begins to move, be raised up from the shelf, so that its under edge shall be free from contact therewith, as will be more fully set forth hereinafter.

Figure 1 is a top view of our improved tightener, the upper portion of the frame-work being removed to show the pulleys around which the belt passes, the shelf upon which it rests when not in use, and the mechanism for tightening the same. Fig. 2 is a side elevation of the device, showing the frame-work which holds the parts in position, the belt upon the pulleys, the tightening-roller, the frame which carries it, and the mechanism for adjusting said frame. Fig. 3 is a view showing a portion of the frame-work and the clamp or frame to which the vibrating bar or frame which carries the roller is attached.

Corresponding letters refer to corresponding parts in the several figures.

In constructing the parts of this device which constitute our invention a frame of

metal such as is shown at E is provided, and secured to any convenient vertical support. This frame is to be provided with slots, as shown at Fig. 3, so that the bolts which secure it to the vertical support may have play in it, in order that it may be set at a slight angle to the face of the belt, for a purpose soon to be described. At each end of this frame there are flanges formed, at a right angle to its broadest surface, which project far enough therefrom to admit of there being a bolt or pin, F, passed down through them for the purpose of forming a pivotal point upon which the bar or frame which carries the tightening-pulley turns, the frame E turning on the stud e. To the upper end of the bolt or pin F an eyebolt, G, or other equivalent device is attached, while over its lower end a plate of metal, G¹, is passed, which plate is attached to the swinging bar H, upon the top of which a bracket of metal, G², is secured, and through the upwardly-projecting flanges of which the eyebolt passes, and in which it is secured by nuts. The parts last described form a joint, by which the lever H is hinged to any suitable post or support, thus allowing the outer end of this swinging lever to have a sufficient range of motion to cause the pulley H¹ which it carries to act upon and tighten the belt. The end of lever H to which the tightening-pulley is secured is bifurcated or otherwise prepared for the reception of the pulley, and may have attached to it a yoke, H², for guiding the belt. Near the outer end of the swinging lever H there is attached a plate of metal, H³, or other suitable device for attaching to the lever a rope or ropes or a chain, I' I', for the purpose of operating the tightener. One of these ropes or chains is fastened to one side of the lever H, and leads to and over a pulley or sheave, and has a weight attached to it for the purpose of drawing the pulley or sheave away from the belt when permitted to do so. To the opposite side of the lever or the plate upon it there is fastened another or the same rope or chain, which is led to and around the shaft K, which is placed at any suitable point to receive it. Upon the shaft K there is a hand-wheel or other suitable device for giving a rotary motion to the shaft, so that when the belt has been slackened and permitted to fall upon the table or

platform, if the shaft K is rotated the rope or chain leading from it to the swinging lever H will bring the pulley H' in contact with the belt, and carry it into the position shown in Fig. 1, in doing which, owing to the fact that the face of the pulley is set at a slight angle to that of the belt by means of the frame E, the belt will be raised from the table, so as not to be worn by coming in contact with it.

Whenever it becomes desirable to raise or lower the outer end of the lever H to cause it to conform to the position of the belt or to give direction thereto it may be done by turning the nuts upon the eyebolt G, they being turned toward the frame E for raising it and away from it for loosening it.

What we claim as our invention, and desire to secure by Letters Patent, is—

1. The combination and arrangement of the

frame E, bolt or pin F, eyebolt G, and lever or frame H, the parts being constructed and arranged substantially as shown and described, for the purpose of allowing the tightening-pulley to be set at an angle to the surface of the belt and of furnishing the means for raising and lowering the outer end of the lever or frame.

2. We claim the combination of the lever or frame H, weight I, ropes or chains I', and shaft K, substantially as and for the purpose set forth.

In testimony of which invention we have hereunto set our hands.

JAMES ALBERTSON.
DANIEL W. MARMON.
